UNITED STATES PATENT OFFICE.

THOMAS SHIPLEY, OF WAYNESBOROUGH, PENNSYLVANIA, ASSIGNOR TO
THE FRICK COMPANY, OF SAME PLACE.

DESIGN FOR A FRAME FOR ICE-MACHINES.

SPECIFICATION forming part of Design No. 26,490, dated January 5, 1897.

Application filed November 28, 1896. Serial No. 613,838. Term of patent 14 years.

To all whom it may concern:

Be it known that I, THOMAS SHIPLEY, a citizen of the United States, residing at Waynesborough, in the county of Franklin and State 5 of Pennsylvania, have invented and produced a new and original Design for a Frame for an Ice-Machine; and I do hereby declare the following to be a full, clear, and exact description of the same, reference being had to the accompanying drawings, forming a part thereof.

My invention consists in a new and original design for the frame of an ice-machine, and is fully disclosed in the following description and claim, reference being had to the accompanying drawings.

Figure 1 is a perspective view illustrating my invention, showing the engine bed and cylinder attached. Fig. 2 is a side view, the cylinder being removed. Fig. 3 is another 5 side view showing the engine-bed removed, the figure being partly in section. Fig. 4 is a top plan view, also partly in section.

In the drawings, *a* represents the upright standard, which is rectangular in cross-section and is provided with four upwardly-tapering faces *b b c c*. At the upper end of the standard *a* is a horizontal platform *d*, of substantially the width of the top of the standard, but of considerably greater length, the 5 ends *d' d'* of said platform, which are rounded, extending a considerable distance beyond the top of the standard and being connected therewith by curved brackets *e e*. The faces *b b* of the standard are recessed at *b' b'*, the central portion of the walls of said recesses being parallel to each other, and from each of said parallel portions a flange *f* extends at right angles, part inwardly and part outwardly, the outer parts of said flanges *f* ex-

tending beyond the inclined faces or sides 40 *b b* of the standard and having perfectly vertical edges, as shown. The platform *d* has its ends overhanging the recessed faces *b b* of the standard.

The faces *b b* have at their lower ends outwardly-projecting parts *g*, having the rectangular faces *g'*, the semicylindrical extension *g''*, and at each side curved flanges *g'''*, extending from the inclined face *b* downward to the side faces *g'*. The faces *c c* are each provided 50 with an oval aperture *h*, and one of said faces *c* is provided with an outwardly-extending portion *k* at one side of the aperture *h*, having a curved upper face *k'*, straight sides, and a vertical front face having an oblong opening *k''* therein, as shown in Fig. 3. From the face *k'* of the part *k* a casing *l* extends outwardly from the standard *a*, said casing having an elongated aperture *l'* in each side.

The gist of my design consists in the single 60 rectangular standard, tapering from top to bottom on all sides, the platform surmounting the standard, of greater length than width and having its ends projecting out from the standard over two opposite sides of the same, 65 and the flanges *f f*, projecting from the inclined faces *b b* and having their outer edges vertical.

What I claim, and desire to secure by Letters Patent, is—

The design for the frame of an ice-machine, substantially as herein described and shown.

In testimony whereof I affix my signature in presence of two witnesses.

THOMAS SHIPLEY.
